(57) **CLAIM**

The ornamental design for an air outlet for vacuum cleaner, as shown and described.

DESCRIPTION

1. Air outlet for vacuum cleaner

1.1 : Front perspective view

1.2 : Bottom perspective view

1.3 : Front

1.4 : Left

1.5 : Top

1.6 : Bottom

1.7 : Enlarged

1.8 : Cross sectional

1.9 : Reference view

Reproduction 1.7 is an enlarged view of the encircled portion in reproduction 1.1; reproduction 1.8 is a vertical cross-sectional view of reproduction 1.5; reproduction 1.9

(Continued)

shows a state in use of the claimed design and portions shown in broken lines are disclaimed.

1 Claim, 9 Drawing Sheets
